RECYCLING CONTROL SYSTEM AND APPARATUS FOR OIL BURNERS AND THE LIKE

James McK. Relley, Merion, Pa., assignor, by
mesne assignments, to General Electric Com-
pany, a corporation of New York

Application February 28, 1930, Serial No. 432,145

12 Claims. (Cl. 158—28)

The present invention relates to control apparatus for heating systems operated by oil burners, gas burners and the like, and particularly refers to means for controlling the quantity of fuel injected into the combustion chamber at any one operation to the safe amount which can be expanded in the chamber under any conditions and for repeating the operation a predetermined number of cycles to overcome the difficulties in starting ignition.

The principal object of the invention is to provide means for automatically controlling the functions of a heating system in a positive and safe manner in accordance with the temperature demands or requirements.

Another object is to provide means for automatically limiting the starting ignition attempts to periods of short duration and repeating the starting ignition attempts a predetermined number of times or until the fuel has been ignited and for shutting down the entire system if the fuel fails to ignite at the last attempt.

Another object is to provide positive timing means independent of external effects for controlling the starting attempts to ignite the fuel at predetermined intervals and also for controlling the time range of operation of thermostats associated with the heating system for maintaining the temperature constant.

Another object is to provide positive electricaly-operated timing means dependent solely upon frequency as, for example, a synchronous motor which is independent of voltage variations.

Another object is to provide means for automatically resetting the control apparatus of the system to its initial or safe condition when ignition has been established.

A further object is to provide means for manually resetting the control system to its original condition in case ignition fails to take place at the last attempt.

A still further object is to provide means for automatically resetting the control apparatus of the system to its initial or safe condition in case of power failures or loss of flame or combustion.

Other objects and advantages of the invention will appear more fully hereinafter from the following detailed description taken together with the accompanying drawings, in which:

Fig. 1 is a schematic wiring diagram of the improved control system showing the circuit relation of the various elements essential to its operation;

Fig. 2 is a continuation of the control circuit

of Fig. 1 showing the furnace and associated control apparatus;

Fig. 3 is a front view of the recycler used in the system;

Fig. 4 is a side view thereof looking at the device from the left;

Fig. 5 is another end view looking at the device from the right;

Fig. 6 is a sectional view taken on line 6—6 of Fig. 3; and

Fig. 7 is another sectional view taken on the line 7—7 of Fig. 3.

Fig. 8 shows a modification of the cam for shifting the control from the "day" to the "night" thermostats.

Existing control apparatus for oil burners, for example, permits only one attempt for the burner to ignite the fuel and get under way. The reason for this is brought about by the necessity for eliminating minor service difficulties generally due to loss of head on the fuel pump, extra viscosity of the oil in the case of an oil burner, leaking foot valves, water slugs in the oil line, temporary ignition troubles, failure of the blower supplying air to the combustion chamber, etc. In the case of gas burners, other analogous difficulties may arise. In having the availability of only one attempt to start the burner in operation, sufficient time must be allowed to overcome the aforementioned difficulties to prevent an abnormal amount of servicing. If sufficient time be allowed to satisfactorily eliminate them, under certain conditions, the burner will produce a flare-back, causing the furnace doors to be blown open and, in some cases, the "puff" or explosion produced may be sufficient to cause damage to the heater itself.

The present invention provides means for controlling the quantity of fuel injected into the combustion chamber at any one operation to the safe amount in the form of a short "shot" or jet which can be expanded in the combustion chamber under any conditions and repeating the operation as many times as desired to provide sufficient pumping time to overcome the minor difficulties outlined above with sufficient time between pumping periods to allow the fuel if sprayed, atomized or vaporized in the pumping periods to be disposed of either by the natural draft of the boiler if the boiler is hot or to be condensed against the cold surfaces of the combustion chamber if the boiler is cold.

In order to carry out this method of controlling the quantity of fuel injected to a safe amount, it is essential to provide positive timing means

for the operations of the control mechanism which is unaffected by external influences and, thereby, controlling the operations of the burner itself. To insure a positive means of timing, the invention contemplates in the present instance, the provision of an electrically-operated device such as a small synchronous motor for driving a cam and which accurately and repeatedly gives the same time cycle and which is not affected by voltage variations but depends solely upon the frequency of an alternating current supply thereto for its operation rather than employing the usual means for obtaining time effects in existing control apparatus by the so-called warp switches or thermal timing means. Therefore, one of the features of the invention is the application of a synchronous or frequency motor to control apparatus for timing purposes and for controlling the starting periods of the burner or the time range of the thermostat settings of the system or both.

Referring to Figs. 1 and 2 of the drawings, the system comprises a thermostat A, a starting transformer B, a relay C, a timing cam D, a synchronous motor M, a thermostat control cam E, a recycling mechanism F, a lock transformer J, furnace thermostat H, and ignition transformer I. The furnace thermostat H, in the present instance, may be located in the combustion chamber 78 of the furnace 77 (Fig. 2) or at any other suitable location at which the direct heat of the furnace may affect it when combustion is established. The furnace 77 is, of course, located in the basement below the floor 82 and transmits heat through the hot-water or steam-pipes 79 and 80 to the radiator 81 which is located in the room with thermostat A. Of course, it is understood that the control circuit and apparatus of the invention are applicable to furnaces of any type of heating systems, such as hot air, vapor, pipeless furnace, etc., without departing from the scope of the invention. The combustion chamber 78 may be supplied with sprayed, atomized, vaporized or gaseous fuel from the supply tank 90, or any other source of fuel supply, by means of the pump 86 through pipe 85 and nozzle or burner 84. An air pump 88 supplies the necessary combustion air. The fuel is then adapted to be ignited by an electric spark produced at the spark gap 83 across the secondary of ignition transformer I when it is energized. The ignition transformer I may be located in the vicinity of the furnace 77 with its secondary leads terminating in a spark gap 83 in the combustion chamber 78. The thermostat A comprises two heat-responsive elements 1 and 2 which are adapted to open and close contacts 3, 4 and 5, 6, respectively, in accordance with temperature changes at a desired location as, for example, a room in a dwelling or other building. As indicated in the figure, the elements 1 and 2 of thermostat A are adapted to close the circuit through the secondary of the starting transformer B when they engage contacts 4 or 6 through the conductors 7 or 8, the conductor 9, the winding 10 of relay C, conductor 11, contacts 12 and 13, which may be opened and closed by means of the timing cam D, through conductor 14 and through contacts 15-16 or 16-17, depending upon the position of the thermostat control cam E, through conductors 18 or 19, back to the thermal elements 1 or 2, respectively. Element 1 may be placed in circuit through contacts 15 and 16 by means of the cam E when the cam is in the position shown and the follower 20 engages portion 21 of the cam. A similar portion

22 is provided on the cam E, which when it strikes the follower 20, raises it, making a circuit through contacts 16 and 17 to the thermal element 2. Element 1 may be adjusted to be actuated at one temperature, while element 2 may be adjusted to respond to another temperature and, in this instance, responds to a lower temperature than element 1 so that element 1 may be utilized during the day hours indicated as "Day range" when a higher temperature is required in the room and element 2 may be utilized during the night hours indicated as "Night range" when a lower temperature is generally desired. The cam E is designed to rotate one revolution in twenty-four hours and the proportions of the facings 21 and 22 of the cam may be designed for any interval desired. For example, the face portion 21 may be made so as to constitute a longer path of travel for the follower 20 than the face portion 22 in order that the element 1 of thermostat A may be utilized for a longer period than element 2. The cam may easily be designed to be adjustable so that the lengths of the portions 21 and 22 may be varied to any predetermined desired extent. In Fig. 8 is shown such a cam. It will be noted that the cam comprises two parts, the part E' and the part E₁ provided with collars 102 and 103 and having raised portions 22' and 22₁. The parts are mounted adjacent each other on the cam shaft S and may be rotated with respect to each other on the camshaft if setscrews 100 and 101 are released. Thus, it will be seen that by properly shifting the two parts with respect to each other, the raised portions 22' and 22₁ will together provide a longer raised portion than either one individually. The cam E may be rotated by means of the motor M, which is of a well-known type of a synchronous motor having a shaft geared thereto for a speed of one revolution per minute, and by means of suitable gears the cam may be given a speed of one revolution in twenty-four hours.

The timing cam D is also rotated by means of the synchronous motor M and, by means of another set of gears, is made to rotate a half revolution per minute. The cam D is provided with peripheral recesses 23 spaced 90° apart. As the cam D rotates, it actuates a follower 24 which, in turn, opens and closes the contacts 12 and 13. Each time the follower enters one of the recesses 23, the contacts 12 and 13 are closed, while when the follower is raised, by the faces 25 of the cam, the follower 24 causes the contacts 12 and 13 to be opened. It will be seen that since the cam D rotates a half a revolution per minute and the recesses 23 are 90° apart, the contacts 12, 13 will be closed every thirty seconds and remain closed for a relatively short interval and opened again by the follower 24 when it strikes the raised portions 25 of the cam. The timing of the closing of the contacts 12 and 13 is positive and accurate because of the fact that the motor M is a synchronous motor and depends solely upon frequency for its speed. As long as the frequency remains constant, its speed remains constant, in spite of any voltage variations on the line. It may be designed to operate on a frequency of sixty cycles or any other suitable frequency commercially available in practice. The motor M is energized from the 110 volt alternating current source of the desired frequency from the terminal L through conductor 26, conductor 27, conductor 28, through conductor 29 to the other side of the 110 volt line to the terminal G which in the present instance is grounded.

Obviously separate synchronous motors could be used to drive cams D and E instead of a single motor as disclosed herein. In such case the motors and their respective cams could be located at different positions. It should be noted also that the design of cam D or the speed of its shaft may be varied to give any desired duration and frequency to the open and closed periods of contacts 12 and 13.

- 10 The circuit of the frequency motor M is closed at all times and never interrupted. When cams D and E are in the positions indicated, element 1 of thermostat A is in circuit and the heating system is operated on the daylight range, the circuit 15 being made from element 1 through conductor 18, contacts 15 and 16, conductor 14, contacts 13 and 12, conductor 11, winding 10 of relay C, conductor 9 through the secondary of the starting transformer B, conductor 8, conductor 7 and 20 through contact 4 back to element 1. When the circuit is thus closed, the winding 10 of the relay C becomes energized and also the secondary of the starting transformer B. The primary of transformer B is energized from terminal L 25 through conductor 26, contacts 27' and 28', conductor 29' and through conductor 30 to the terminal G of the other side of the line. However, no current flows in the secondary until its circuit is closed by means of the contacts 12 and 13. 30 As soon as the circuit is closed, the winding 10 of relay C becomes energized, as hereinbefore stated, closing the contacts 31 and 32 of the relay which closes the circuit of the motor 87 of the pump 86 and the primary of the ignition transformer I. The circuit of the pump motor 87 is made 35 from terminal L through conductor 26, contacts 27' and 28', conductor 29', conductor 33, contacts 32 and 31, conductor 34, conductor 35, terminal M₁, through the motor via conductors 35' and 36' 40 to terminal M₂, and through conductor 36 back to terminal G of the 110 volt line. While the motor circuit is momentarily closed, it causes the fuel pump 87 to inject a short "shot" of fuel into the combustion chamber 78 of the furnace 77 through 45 burner 84 where it is adapted to be ignited by a spark produced across the gap 83 of the secondary of ignition transformer I. Simultaneously, the primary of the transformer I is closed from the junction point 37 of conductors 34 and 35, 50 through conductor 38, through thermal element 39 of thermostat H, contact 40, conductor 41, through the primary winding of I and through conductor 29 to terminal G. The secondary of the ignition transformer I produces the required 55 spark in the combustion chamber and if the conditions are exact, the fuel in the chamber will be ignited and combustion established. However, if conditions were such that ignition would not take place in the combustion chamber at the 60 instant that the contacts 31 and 32 of the relay C are closed, the cam D opens contacts 12 and 13, thus deenergizing the winding 10 and breaking the circuit of the primary of transformer I and of the pump motor 87. The short "shot" of fuel 65 which had been injected by the pump is then permitted to escape through the draft of the furnace if the furnace is hot or to condense in the combustion chamber if the furnace is cold as explained hereinbefore. The fact that the 70 fuel is injected in just a short "shot" or in other words just the necessary quantity required to start ignition and prevented from continuing to be injected, large quantities of fuel are prevented from accumulating in the chamber which when 75 ignition would finally take place might cause an

explosion sufficiently great to destroy the furnace and possibly wreck a portion of the building in which it may be located. As cam D continues to rotate the contacts 12 and 13 are again closed by the cam D, the winding 10 is again energized, 5 the arm 42 of the relay C is attracted thereby and contacts 31 and 32 are again closed and another jet of fuel is injected into the combustion chamber and a spark established across the secondary of transformer I. As the arm 42 is attracted by the winding 10, it actuates a connecting arm 71 which is connected to arm 42 and causes the rod 44 of the recycler F to be moved upward by the pawl 45. The rod 44 may be cylindrical in shape and provided with circumferential 10 grooves 46 which constitute sort of a ratchet which is engaged in one groove at a time, each time that the pawl 45 is actuated by the arm 42 through connecting rod 71. As the rod 44 rises one notch, it is held in place by means of a spring element 47. After the cam D has closed the contacts 12 and 13 five times or more, depending on 15 the number of grooves provided on rod 44, and ignition has not been established, the rod 44 will finally be raised to such a position that the head 20 48 of the rod 44 will strike the pivot arm 49, causing the contacts 27' and 28' to be opened by virtue of the spring qualities of contact arm 27'. As soon as contacts 27' and 28' are opened, the primary 25 of the transformer B is open-circuited and the secondary thereof thereby deenergized, causing the deenergization of winding 10 and the release of the arm 42 of the relay C. No circuits can now be established until the contacts 27' 30 and 28' are reclosed or reset manually. This 35 function prevents the taking place of spontaneous ignition which might otherwise be produced. The repeated notching action just described causes the rod 44 and associated parts to function as an automatic mechanism for accurately counting the number of attempts to establish combustion and the number of these attempts is limited accurately by the number of grooves provided on the rod 44. If, however, in 40 any cycle of the cam D, combustion is established, the thermal switch mechanism or flame detector H, which may be located in the combustion chamber, will operate, moving its thermostat 39 from the contact 40 which is in the cold position to the contact 50 or the hot position, causing a circuit to 45 be made from terminal L through conductor 26, contacts 27' and 28', conductor 29', conductor 33, contacts 31 and 32, conductor 34, junction 37, conductor 38, element 39, contact 50, conductor 51, through the primary of the locking transformer J, 50 conductor 52 and through conductor 30 back to the terminal G on the other side of the 110 volt line. The circuit of the primary of the transformer J being closed causes the energization 55 of its secondary and also of the winding 10 of the relay C. The winding 10 now becomes permanently energized or "locked" by reason of the primary of the transformer J being energized through the thermostat H, thus keeping the contacts 31, 32 closed as long as combustion is maintained. At the same time, a circuit is completed from the junction point 37 through conductor 38, element 39, contact 50, conductor 51, terminal 60 53 of the locking transformer J, conductor 54 through the winding 55 of the recycler F, through conductor 56 and through conductors 28 and 29 back to terminal G of the other side of the line. The energization of the winding 55 causes the rod 57 to be pulled down against the tension of 65 the spring 58 which is seated between collars 70 75

59 and 60 on the rod 57 and causes the spreading apart of pawl 45 and spring element 47 to disengage the rod 44 and allowing it to drop to its original position against the guide 61. Thus, it will be seen that the recycler is automatically reset by means of the winding 55 when combustion is established. If combustion should cease for any reason, the thermostat H will again be actuated to its cold position against contact 40 thereby breaking the contact between the element 39 and contact 50, causing the deenergization of the primary of transformer J, thereby deenergizing the winding 10 by virtue of the secondary of transformer J not receiving energy from its primary. As soon as the winding 10 is deenergized, the contacts 31 and 32 are broken breaking the circuit to the pump and blower motor. If the thermostat A is still calling for heat the cam D will immediately cause periodic energization of the motor 87 and the ignition system to again start up the burner. If the thermostat is not calling for heat, nothing happens until the thermostat A again calls for heat since the circuit through the electro-magnet 10 is broken at the thermostat. Also in case of power failure at the terminals L and G, the transformer J will be deenergized and the whole system rendered inoperative.

When combustion has been started and maintained, the temperature in the region in thermostat A will rise until the temperature is reached for which the element 1 is set, at which time, the element 1 will break the contact 4 and close the contact 3. As soon as contact 3 is closed, the winding 10 becomes short-circuited through element 1, contact 3, conductor 61, conductor 9, to one side of the secondary of transformer J, from the other side thereof to conductor 11, contacts 12, 13, conductor 14, contacts 16 and 15 and through conductor 18 back to element 1. The short-circuiting of the winding 10 causes the arm 42 of the relay C to be released and the circuit of the pump motor to be broken by contacts 31 and 32. When the temperature drops below the setting of the thermostat, the element 1 again engages contact 4 and the system set into operation as before.

Referring to Figs. 3 to 7, the recycler F comprises an insulating panel 63 on which are mounted the cylindrical casing 65, which holds the relay winding 55 (Fig. 1), the terminal binding posts 66 and 67, which are adapted to be connected to the primary of the starting transformer B, and the terminal L of one side of the 110 volt supply line, respectively, as indicated in Fig. 1. To the terminal 67 is connected a spring contact element 68 on which is mounted the contact 27' which is adapted to engage contact 28' and close the circuit through terminal 66. The normal position of the contact element 68 is such that contacts 27' and 28' are in closed relation and the element 68 is maintained in this position by means of the tooth 69' on the locking element 69 which is fastened to the panel 63 by means of the bracket 70. When the locking element 69 is raised, the element 68 moves to the left by virtue of the spring action thereof and breaks the contacts 27' and 28'. The locking element 69 is adapted to be raised by the knob 48 which is integral with the rod 44. The rod 44 is provided with the circumferential grooves 46 which form a sort of rack and the grooves are adapted to be engaged by the pawl 45 to raise the rod 44 one notch each time that the rod 43 is actuated by means of the arm 71 which is adapted to

be connected to the armature 42 of the relay C (Fig. 1). It will be apparent that each time that the relay 42 closes the contacts 31, 32, the arm 71 moves with it, thereby actuating the rod 43 and the pawl 45 which are pivotally mounted in the bracket 72 by means of the rod 73. As the pawl 45 raises the rod 44 one notch, the rod is held in that position by means of the spring element 47 which bears against the rod 44 at an angle thereto so that its upper edge engages the first notch. When the armature 43 of the relay C is released, the weight 74 functions to drop the pawl 45 to its lowered position. After the armature 42 of the relay C has been actuated five times in the present instance, or as many times as there are 15 circumferential grooves 46 on the rod 44, the rod 44 will have reached its maximum raised position, that is, the last circumferential groove is engaged by the pawl 45 and raised so that the knob 48 strikes the locking element 69, thereby 20 releasing the spring element 68 from its locked position and breaking the contacts 27' and 28', as explained in the description of Fig. 1. The breaking of the contacts 27' and 28' breaks the 110 volt supply circuit, so that all of the elements 25 of the system are rendered inoperative with the exception of frequency motor M which is in circuit at all times. An armature 57 is provided which is adapted to be actuated by the winding 55 of the relay 65, as explained hereinbefore and 30 ignition has been established in the combustion chamber. In that case, the armature 57 is drawn downward against the force of the spring 58 which is compressed, causing the tapered end 75 of the rod 76 to pass between the pawl 45 and 35 spring element 47, thereby spreading them sufficiently to permit the rod 44 to drop to its original position, thereby resetting the recycler automatically so that it will be available for operation the next time that ignition is to be again initiated. 40 The rod 76 is, of course, attached to the armature 57 in order that it may be actuated thereby. When winding 55 of the relay 65 is deenergized, the armature 57 is returned to its normally raised position by means of the spring 58 which is confined between the collar 60 and the nut 59. As the rod 76 is withdrawn from between the pawl 45 and the spring element 47, the spring element 45 is caused to bear against the rod 44. The rod 44 is guided in its travel by means of the guides 61 50 and 62 which are integral with the bracket 72.

It is believed that the operation of the recycler F will be apparent from the foregoing description together with the description of the operation of the entire system which has been explained with respect to Fig. 1.

While I have shown only one embodiment of the control system and the apparatus connected therewith, other changes and modifications may be apparent therein to those skilled in the art 60 without departing from the scope of the invention and I, therefore, desire to be limited only by the scope of the appended claims.

I claim:

1. The combination with a heating system including means for feeding fuel, and an igniter, of a control system therefor comprising means for controlling said fuel-feeding means and igniter to attempt to initiate combustion at predetermined temperature conditions, means including 70 electromagnetic means and intermittent energizing means therefor for rendering said second-mentioned means effective a predetermined number of times at selected intervals for periods of short duration, and means operative with said 75

electromagnetic means for rendering said control system ineffective when combustion fails to take place during the last time that said second-mentioned means is rendered effective.

5. 2. The combination with a heating system including means for feeding fuel and an igniter, of a control system therefor comprising means for controlling said fuel-feeding means and igniter to attempt to initiate combustion at predetermined temperature conditions, electromagnetic means for rendering said second-mentioned means effective, intermittent circuit controlling means for causing the energization of said electromagnetic means whereby it is actuated at selected intervals for periods of short duration, positive timing means for actuating said fourth-mentioned means to produce the selected intervals, means for limiting the number of times said electromagnetic means may be actuated and operative therewith, and means adapted to be actuated by said last-mentioned means for rendering said control system ineffective when combustion fails to take place during the last actuation of said electromagnetic means.

25. 3. The combination with a heating system including means for feeding fuel and an igniter, of a control system therefor comprising means for controlling said fuel-feeding means and igniter to attempt to initiate combustion in said first-mentioned means at predetermined temperature conditions, electromagnetic means for rendering said second-mentioned means effective, intermittent circuit controlling means for causing the energization of said electromagnetic means whereby it is actuated at selected intervals for periods of short duration, electrically controlled timing means for actuating said fourth-mentioned means to produce the selected intervals, means for limiting the number of times said electromagnetic means may be actuated and operative therewith, and means adapted to be actuated by said last-mentioned means for rendering said control system ineffective when combustion fails to take place during the last actuation of said electromagnetic means.

45. 4. The combination with a heating system including means for feeding fuel and an igniter, of a control system therefor comprising means for controlling said fuel-feeding means and igniter to attempt to initiate combustion in said first-mentioned means at predetermined temperature conditions, electromagnetic means for rendering said second-mentioned means effective, intermittent circuit controlling means for causing the energization of said electromagnetic means intermittently whereby it is actuated at selected intervals for periods of short duration, electrically controlled timing means comprising a synchronous motor the operation of which depends only on the frequency of an alternating current independent of any voltage variation in said current for actuating said fourth-mentioned means to produce the desired intervals, means for limiting the number of times said electromagnetic means may be actuated and operative therewith, and means adapted to be actuated by said last-mentioned means for rendering said control system ineffective when combustion fails to take place during the last actuation of said electromagnetic means.

5. 5. The combination with a heating system including means for feeding fuel, ignition means therefor, of a control system therefor comprising means for controlling said fuel-feeding means and said ignition means, motor-operated timing

cam mechanism for operating said controlling means for attempting to initiate combustion for periods of predetermined short duration at definite predetermined selected intervals, and a pawl and ratchet means operated by said controlling means to disable said control system when combustion fails to take place, said disabling means being adapted to be manually reset to render said control system effective, and means operatively associated with said control system and responsive to combustion for maintaining said fuel-feeding means in operation independently of said motor-operated timing cam mechanism when combustion is established.

10. 6. The combination with a heating system including means for feeding fuel, ignition means therefor, of a control system comprising means for controlling said fuel-feeding means and said ignition means, timing cam mechanism for operating said controlling means for attempting to 15 initiate combustion a predetermined number of times for periods of predetermined short duration at definite predetermined selected intervals, and a pawl and ratchet means operated by said third-mentioned means and rendered effective during 20 the last operation thereof to disable said control system when combustion fails to take place, said fourth-mentioned means having a mechanical locking pawl adapted to be manually reset to render said control system effective, and means operatively associated with said control system and responsive to combustion for maintaining said fuel-feeding means in operation independently of 25 said timing cam mechanism when combustion is established.

30. 7. The combination with a heating system including means for feeding fuel, an igniter, of a control system therefor comprising means for controlling said fuel-feeding means and igniter to attempt to initiate combustion at predetermined temperature conditions, electro-magnetic means for rendering said second-mentioned means effective, intermittent circuit controlling means for causing energization of said electro-magnetic means intermittently whereby it is 35 actuated at selected intervals for periods of short duration, electrically controlled timing means for operating said fourth-mentioned means to obtain the selected intervals, means for limiting the number of times said electro-magnetic means 40 may be actuated and operative therewith, means adapted to be actuated by said sixth-mentioned means for rendering said control system ineffective when combustion fails to take place during the last actuation of said electro-magnetic means, and means rendered operative when combustion is 45 established to simultaneously cause continuous energization of said electro-magnetic means to maintain said combustion and to return said limiting means to its normally starting position.

50. 8. A heating device including electrical means for feeding fuel, an igniter therefor, an electrical control for controlling said fuel-feeding means and igniter including a constant speed motor-operated timing switch mechanism and electro-magnetic switch mechanism controlled thereby for intermittently energizing said fuel-feeding means and igniter at predetermined intervals for initiating combustion, temperature-responsive means movable between two positions and movable to one of said positions for rendering said fuel-feeding and igniter control effective under predetermined temperature conditions, and means responsive to combustion conditions for controlling said electromagnetic switch mechanism to 55 60 65 70 75

- 5 maintain the fuel-feeding means energized when
combustion is established independently of the
operation of said motor-operated timing switch
mechanism, said temperature responsive means
being movable to the other position under other
predetermined temperature conditions for con-
trolling said electromagnetic switch mechanism
to deenergize said fuel-feeding means.
9. A heating device including electrical means
10 for feeding fuel, electrical means for igniting said
fuel, an electrical control for said fuel-feeding
means and said igniting means including a con-
stant-speed motor-operated timing switch mech-
anism and electromagnetic switch mechanism
15 controlled thereby for controlling said feeding
means and ignition means for intermittently
energizing the same at predetermined intervals
for initiating combustion, temperature-responsive
means movable between two positions and mov-
20 able to one of said positions for rendering said
fuel-feeding and ignition control effective under
predetermined temperature conditions, and means
responsive to combustion conditions for deener-
gizing said igniting means, and for controlling
25 said electromagnetic switch mechanism to main-
tain said fuel-feeding means energized independ-
ently of said timing cam mechanism when com-
bustion is established, said temperature-respon-
sive means being movable to its other position
30 under other predetermined temperature condi-
tions for controlling said electromagnetic switch
mechanism to deenergize said fuel-feeding means.
10. The combination with a heating system in-
cluding electrically operated means for feeding
35 fuel, an electrically operated igniter therefor, of
electromagnetic switching means for controlling
said fuel feeding means and igniter to attempt
to initiate combustion, means including an elec-
tric motor operated timing switch mechanism for
40 controlling the energization of said electromag-
netic switching means for repeating said igni-
tion attempts a predetermined number of times
at definite predetermined selected intervals, and
means operative to control the energization of

said electromagnetic circuit controlling means to
hold said fuel feeding means in continuous op-
eration and to prevent the repetition of said igni-
tion attempts independently of said motor op-
erated timing switch mechanism when combus-
tion is established. 5

11. The combination with a heating system in-
cluding means for feeding fuel, an igniter there-
for, a control system therefor, comprising a source
of electrical energy, means including an electro-
responsive switch energized from said source for
controlling said fuel feeding means and igniter
10 to attempt to initiate combustion, intermittent
circuit controlling mechanism for intermittently
deenergizing and reenergizing said electrorespon-
sive switch to repeat said ignition attempts at
selected intervals, means movable from a start-
ing position and operative with said electrore-
sponsive switch for limiting the number of rep-
etitions, combustion responsive means for de-
energizing said igniter when combustion is es-
tablished, and electrical means rendered opera-
tive by said combustion responsive means when
combustion takes place for causing said limiting
means to return to the starting position whereby
25 said combustion is maintained. 20

12. The combination with a heating system in-
cluding means for feeding fuel, an igniter there-
for, of means including an electroresponsive de-
vice for controlling said fuel feeding means and
30 said igniter to attempt to initiate combustion, in-
termittent circuit controlling mechanism for de-
energizing and reenergizing said electrorespon-
sive device to repeat said ignition attempts at
selected intervals, means movable from a starting 35
position through a series of steps for limiting the
number of repetitions of ignition attempts, elec-
troresponsive means for causing said limiting
means to return to the starting position, and com-
bustion responsive means for rendering said elec-
troresponsive means effective when combustion is
40 established. 40
